SAFETY INTERVAL LOCK MECHANISM

Paul S. Millice, Hamilton, Ohio, assignor to Herring-Hall-Marvin Safe Company, New York, N. Y., a corporation of New York

Application March 26, 1936, Serial No. 70,987

19 Claims. (Cl. 70—269)

My invention relates to lock mechanism, and has for its primary object the provision of novel means for insuring a safety interval for lock release.

5 It is a further object of my invention to provide a delay in novel manner between the beginning of unlocking movement of a lock and completion of the unlocking movement, in order to provide a time interval in the unlocking of the lock as a safety feature in case of a hold-up or an attempt at robbery.

10 My improved device is intended for association with combination locks, key locks and other types of locks, including bolts, and is for use primarily in connection with safes and wall vaults, but may be used in connection with closets, chests and drawers, and in other relations.

15 My improved device is not intended to take the place of long interval time locks which are used for protection of heavy safes and bank vaults over night, Sundays, holidays and the like, but may be used in connection therewith. It is intended primarily to provide a simple and inexpensive means to prevent the immediate opening of 20 a locked compartment upon the demand of a hold-up man or robber.

25 My invention consists in novel means for preventing the immediate unlocking of a lock; further, in novel means for arresting the unlocking 30 of a lock and insuring lapse of an interval of time before completion of such unlocking; further, in novel means for insuring resetting of the safety mechanism prior to a relocking of a lock; further, in novel means for compelling the unlocking 35 movement of a lock to take place in steps, including a time interval; further, in novel means for automatically controlling the actuation of clock mechanism and its duration for determining a safety time interval throughout which delay in 40 opening a lock is insured; and, further, in providing means for a minimum limit of time interval.

45 My invention will be further readily understood from the following description and claims, and from the drawings, in which latter:

Fig. 1 is a front elevation of an exemplification of my invention shown in connection with a combination lock on a vault door, partly broken away.

50 Fig. 2 is a horizontal section of the same, taken on the line 2—2 of Fig. 1, and partly broken away.

Fig. 3 is a vertical section of the same, taken on the irregular line 3—3 of Fig. 5, and partly broken away.

55 Fig. 4 is a horizontal section of a detail of the same, taken on the line 4—4 of Fig. 5.

Fig. 5 is a vertical section, taken in the plane of the line 5—5 of Fig. 9, showing the parts in fully locked relation.

Fig. 6 is a similar view, showing the parts in their relation at the beginning of the safety 5 interval in the unlocking movement, and indicating the distance of movement of the lock bolt, the fully locked position of the same being shown in dotted lines.

Fig. 7 is a similar view of my improved device, 10 showing the parts in their relations at the end of the safety interval.

Fig. 8 is a similar view of my improved device, showing the parts in unlocked relation, positions 15 of the lock bolt at previous stages being shown in dotted lines.

Fig. 9 is a horizontal section of my improved device, taken on the line 9—9 of Fig. 1, and partly broken away.

Fig. 10 is a vertical section of a detail, taken on 20 the line 10—10 of Fig. 9.

Fig. 11 is a front elevation of my improved device, employed in connection with a key lock, and partly broken away.

Fig. 12 is a horizontal section of the same, taken 25 on the line 12—12 of Fig. 11.

Fig. 13 is a vertical section of a detail of the same, taken on the irregular line 13—13 of Fig. 14.

Fig. 14 is a vertical section of the same, taken 30 on the line 14—14 of Fig. 12, partly broken away, and showing a modification of my improved device, and.

Fig. 15 is a fragmentary sectional view, taken in the plane of the line 5—5 of Fig. 9, showing a 35 further modification of my improved device.

I have illustrated my invention as employed in connection with a so-called combination or permutation lock in Figs. 1 to 10 inclusive, and have illustrated it as employed in connection with a key 40 lock in Figs. 11 to 14 inclusive. Fig. 14 shows a modification of my improved device. Fig. 15 shows a further modification.

Referring to Figs. 1 to 10 inclusive, the door of a safe vault is exemplified at 21, and has mounted 45 thereon a usual combination lock 22, on a mounting plate 23, rigidly secured to the door. The combination lock is provided with a locking part, exemplified as a lock bolt 24 arranged to coact with a locking arm 25 of a usual bolt work 26. 50

The locking arm is operated by a usual staff 27 journaled in the door, and having a suitable operating handle 28 at its outer end.

55 The combination lock is provided with a casing 31 and is suitably secured to the door. The lock

is provided with the lock bolt 24, which is locked and unlocked by suitable usual tumbler mechanism 32 manipulated by a suitable knob 33, the knob also shifting the lock bolt into locking and 5 unlocking relation.

A clock mechanism or time mechanism is represented at 35 and a control mechanism in association with the lock and the clock mechanism is represented at 36, there being simple connections 10 between the control mechanism and the lock and the clock mechanism for connecting them in operative relation with each other.

The control mechanism is provided with a supporting plate 41. This plate is resiliently 15 mounted on the lock casing, as by being provided with tongues 42 which extend from the body of the supporting plate and form a resilient mounting for the control mechanism, the metal or material of the plate and the form of the 20 tongues providing sufficient resilience for the mounting. Screws 43 pass through spacing collars 44 separating the tongues from the lock casing 31, and are threaded into said casing, the tongues being clamped between the heads of said 25 screws and shoulders 45 on said collars. These spacing collars may if desired be of resilient material.

The tongues 42 and the spacing collars 44 are, however, preferably sufficiently stiff to prevent 30 excessive vibration and contact between the parts of my improved device and the lock to prevent percussion between the same.

The clock mechanism is mounted on the resiliently supported supporting plate 41, as by 35 screws 46 passing through the supporting plate and collars 47 between the supporting plate and the frame rear plate 48 of the clock mechanism and threaded into the plate 48, clamping the clock frame to the supporting plate, whereby the clock 40 mechanism is also resiliently mounted with relation to the control mechanism and to the door to prevent shocks thereto in case of blows upon the door or parts of the lock.

A casing 51 is received about the control mechanism and the clock mechanism and is preferably 45 free of contact therewith. It is secured to the lock casing 31 by screws 52 passing through lugs 53 on the casing 51 and threaded into the casing 31. (Fig. 9.)

50 The clock mechanism 35 may be of any desired construction. It is shown provided with a usual escapement mechanism 58 including a usual balance wheel 59. The escapement mechanism is normally inactive, the clock mechanism running 55 only from the time that opening of the lock is begun to the time of automatic release of the bolt of the lock.

A usual clock spring 61 is provided, which is wound by a shaft 62, about which there is a spring 60 63. The spring 61 unwinds this shaft when the clock mechanism is running. The outer end of the spring 61 is received about a tie rod 64 between the front plate 65 and the rear plate 48 of the clock mechanism.

65 The shaft 62 is provided with a flange 66. It has a sleeve 67 rotatable thereon, which has a ratchet wheel 68 fixed on one of its ends. A pin 69 is fixed crosswise of the shaft in the shaft and serves as an end abutment for the sleeve.

70 A gear 71 and a disk 72 receiving end contact of the spring 61 are mounted loose on the sleeve. Pawls 73 are pivoted to the gear, and are resiliently held in engagement with the teeth of the ratchet wheel 68 by springs 74 fixed to said gear.

75 One end of the spring 61 is hooked in usual man-

ner to said sleeve, the other end of said spring being looped about the tie rod 64.

The spring 63 presses the sleeve toward the pin 69, and frictionally holds the sleeve to the shaft with sufficient pressure to cause rotation in unwinding direction of the shaft during operation of the clock mechanism and for actuating the devices actuated by said shaft, but permitting rotation of the shaft within the spring for setting purposes.

Suitable clock gearing 75 connects with the gear 71 and is controlled by the escapement mechanism 58. The sleeve 67 is provided with a pin 76, which coacts with the pin 69, extending at right angles to said shaft for conveying rotary motion between the shaft and the sleeve for winding the spring 61 when the shaft is rotated in one direction. The frictional engagement between the shaft 62 and the sleeve 67 permits rotation of the shaft in either direction for setting a pin 77 on said shaft in proper angular relation.

An operating part is clock controlled and is shown as a lever 81 is pivoted on a shoulder screw 82 threaded in the supporting plate 41, and is normally urged in upward direction by a spring 83 contacting a pin 84 fixed in the supporting plate, the upward movement of this lever being limited by a pin 85 fixed in said plate. The lever has a latching extension 86 or keeper, having a keeper face 87.

The lever is provided with an actuator lug 88 arranged to be contacted by the actuating pin 77 fixed to and extending from the shaft 62 and rotating with said shaft for retracting movement of said lever during winding rotation of said shaft, the lever being actuated by said pin during the reverse rotation of said shaft in unwinding direction.

A double bar comprises a bar 91 which is longitudinally and pivotally movable, and a bar 92 which is pivotally movable, forming a combined lever and slide. The bar 91 is a control slide for the clock mechanism, and the bar 92 is a detent for the bolt actuated slide hereinafter described. These bars are pivoted on a shoulder screw 93 threaded to the supporting plate 41. The bar 91 is provided with slots 94, 95, and the bar 92 is provided with a pin 96 received in the slot 95. The screw 93 extends through the slot 94. (Figs. 4 and 5.)

The screw 93 and the pin 96 maintain the bars in parallelism with each other, the walls of the slots 94, 95 riding on the screw and pin respectively during longitudinal movement of the bar 91. The right-hand ends of the combined bars are normally urged downwardly by a spring 97 coacting with a pin 98 fixed in the supporting plate. The bar 91 is provided with a bevel corner 99, and the bar 92 is provided with a latching corner 100, the bevel of the corner 99 sloping toward and protecting the corner 100 when the corner 100 coacts with its keeper.

A movable part exemplified as a longitudinally movable slide 105 is held toward the supporting plate 41 by shoulder screws 106 threaded into the supporting plate and passing through slots 107 in the slide 105. This slide is provided with an opening 108 into which a pin 109 is received, the pin extending from an inside portion of the bolt 24, which extends into the lock casing 31, the pin extending through a slot 110 in the supporting plate. The pin moves with the bolt. This slide may be designated a lock control part.

The slide 105 is provided with a keeper face 114. A detent lever 115 is pivoted to this slide 115

on a shoulder screw 116 threaded into the slide, and a spring 117, contacting the head of one of the screws 106 and movable thereon, normally urges the detent 115 toward the extension 86. 5 Such movement of the detent 115 is limited by its contact with the head of shoulder screw 93. The detent is provided with a detent face 118 which coacts with the keeper face 87.

The lever 81 is provided with an engaging lug 119 which engages one or both of the bars 91, 92 for rocking the same on their pivot 93 and maintaining the same in rocked relation from the time that the lever 81 is moved on its pivot by the actuating pin 77 until the return of the parts 15 to normal positions, namely, throughout the safety interval.

A spring bar 121 is provided with a lateral extension 122 arranged to coact with the escapement mechanism of the clock, exemplified as 20 coacting with the balance wheel 59 thereof. (Figs. 5, 6 and 9.)

The spring 121 is secured to the supporting plate 41 by having one end thereof clamped between pins 98, 124, on the supporting plate and 25 a screw 125 threaded in the supporting plate, for rigidly securing this end to the supporting plate. The spring has a depending portion 126, a bent portion 127 and an upwardly extending portion 128, from which latter the lateral extension 122 30 projects.

The bar 91 is arranged to flex the spring for moving the lateral extension 122 thereof in an arc which is eccentric to and flatter than the circle of the outer periphery of the balance wheel. 35 During the first part of the movement of the lateral extension, when the spring is moved by the bar 91, the frictional engagement between such lateral extension and the outer periphery of the balance wheel moves the balance wheel about its 40 axis for starting actuation of the clock mechanism, and freeing the balance wheel during the latter portion of its movement, so that the balance wheel will continue its oscillations after it is free from said spring.

45 The balance wheel continues to oscillate under the influence of the clock spring 61 throughout the duration of time set for the safety interval, at the end of which time the bar 91 and the spring 121 are automatically returned to normal positions, with the lateral extension 122 contacting the balance wheel for automatically stopping the latter and causing cessation of operation of the clock mechanism.

A winding wheel 131 is attached to the shaft 55 62 for rotating the shaft and being rotated thereby. This wheel has a series of time indications 132 around its flange 133. These time indications are exemplified as zero to 30, representing minutes in time intervals of five minutes. 60 Durations of angular movements of the shaft 62 are represented by these time values which may be of desirable durations.

There is an indicating mark 134 on the casing 51 with which the time indications on the 65 wheel are arranged to register. The normal position of the wheel is a registry of the zero indicating mark thereon with the indicating mark on the casing. The winding wheel is preferably spaced from the casing 51 and the shaft 62 passes 70 through an enlarged hole 135 in said casing for desired safety vibrations of the control mechanism and clock mechanism.

The frictional connection between the shaft 62 and the clock spring 61 permits manual rotation of the wheel 131 and the pin 77 thereon 75

without affecting the clock mechanism, and the pin 69 thereon which coacts with the pin 76 on the sleeve 67 insures sufficient winding of the clock spring, so that the settings of the indicator or winding wheel also insures sufficient winding of the clock to avoid running down of the clock during locked relation of the closure. 5

If the wheel 131 be turned by hand to the extent of an angular movement, so as to register the numeral 10 thereon with the indicating mark 134, 10 an interval of ten minutes will elapse between the time when the unlocking of the lock is begun and the time when the unlocking can be completed.

This would make it necessary for the hold-up man or robber to wait ten minutes after he has 15 compelled an attendant to begin opening the safe or compartment, before the safe or compartment can be actually opened to enable the attendant or hold-up man to gain entrance to the safe or compartment for its contents. 20

The theory is that this interval of time, which may be arbitrarily selected upon previous locking of the door, and in the present exemplification may be anywhere up to thirty minutes, outside 25 help may be obtained or some circumstance will arise to prevent the hold-up or robbery, or will result in the departure of the hold-up man or robber without committing his crime.

The normal position of the parts is shown in 30 Fig. 5, with the pin 77 in the position it will assume with the dial or winding wheel 131 set at a duration of ten minutes.

It may be here stated that the door is supposed to be closed and locked except at such short intervals during which it may be necessary to obtain access to the safe or compartment, so that the parts of the mechanism are normally in 35 locked relation with the door closed.

In this connection the positions of the pin 77, 40 the lever 81, the bars 91, 92, the slide 105 and 45 the detent 115 thereon, and the positions of the keeper face 114, the pin 109 and the bolt 24 are to be noted.

It will be assumed that it is desired to open the 45 door either by the attendant to obtain lawful access to the interior of the compartment or upon the demand of a hold-up man or robber. The setting of the combination of the lock and the attempt to move the bolt 24 of the lock in unlocking direction by manipulation of the knob 33, 50 permits movement of the lock bolt in unlocking direction only to a small extent, as indicated by the space between the dotted end of the bolt, which represents the original position of the bolt, and the full line representation of the lock bolt in 55 Fig. 6, the lock bolt being still in locking relation.

Such slight movement of the lock bolt in unlocking direction, through the medium of the pin 109 thereon coacting with the slide 105, moves the slide to similar extent, thereby moving the 60 bar 91 endwise and actuating the spring 121 and its lateral extension 122, whereby this lateral extension by means of its frictional contact with the balance wheel 59 sets this balance wheel in motion and moves away from the balance wheel 65 for continuation of operation of the clock mechanism.

Further movement of the slide 105 is, however, arrested by contact of its obstructing keeper 114 with the end of the bar or detent 92, preventing 70 the unlocking of the lock bolt. This is the beginning of the safety time interval, the relations of the pin 77, the lever 81, the bars 91, 92, the slide 105 and the detent 115 thereon, and the 75 positions of the keeper face 114, the pin 109, and

the lock bolt 24 being as indicated in Fig. 6 in the present exemplification. It will be noted that the slide 105 has been slightly moved to the left for the distance indicated between the dotted line 5 and the full line representation of the end of the bolt 24, whereby the keeper face 114 has moved the bar 91 endwise, as indicated by the difference in positions of the connecting slots 94, 95, through which respectively the pivot screw 93 10 and the pin 96 extend, it being understood that the bar or detent 92 is pivoted on the pivot bolt and has no endwise movement. These endwise movements of the bar 91 and the slide 105 are arrested by the bar or detent 92. This relation 15 of parts initiates the time interval of such duration as may be determined by the setting of the dial wheel 131.

At the end of this time interval the pin 77 (see Fig. 7) will have engaged and moved the actuated lug 88 and moved the lever 81 downwardly 20 on its pivot 82, causing the lug 119 thereof to move the left-hand ends of the bars 91—92 downwardly for swinging the same on their pivot screw 93 and raising the right-hand ends of these levers. This causes first a tripping of the right-hand end of the bar 91, whereby its inclined face 99 climbs upwardly upon the end of the face 114 25 on the slide 105 for raising the right-hand end of the bar or detent 92 with it, and thereby protecting the locking corner 109 at the right-hand end of the bar or detent 92 against sliding contact with the corner edge of the locking face 114 for preserving these corners and preventing wear and beveling thereof.

Upon such release movement, induced by the recoil of the spring 121, the lateral extension 122 is again moved into contact with the balance wheel at the termination of the safety interval for stopping the clock.

The parts are now in such relation that the movement of the lock bolt 24 may be completed by the turning of the knob 33 of the combination lock for moving the lock bolt in unlocking direction, as indicated by the difference between the 45 dotted positions and the full line position of the lock bolt in Fig. 8.

Comparing Fig. 8 with Fig. 7, it will be noted that the following differences have taken place, namely, the slide 105 has been moved to the 50 left by the completion of the unlocking movement, as will be noted by comparison of the locations of the slots 107 and the shoulder screws 108. The upward swinging movement of the detent 115, whereby its detent face 118 has been 55 brought to rear of the keeper face 87 on the extension 86 of the lever 81, latches the slide 105 against movement to the right, and thereby locks the lock bolt 24 in unlocked position by connection of the walls of its opening 108 with the 60 pin 109 secured to the lock bolt.

The only way in which the lock bolt can be again released for again locking the same is by again winding the shaft 62 in clockwise direction through an angle of movement of the indicator or winding wheel 131, for again moving the pin 77 away from the lever 81 to an angular position determined by the new time setting of the wheel 131, and thereby again winding the spring if the spring has been sufficiently 65 unwound. This new relation of parts is again that shown in Fig. 5, and results in raising of the latching face 87 on the extension 86 of the lever 81 out of engagement with the detent face 118 on the detent 115, permitting the upper face of 70 the detent 115 to ride in locking direction under

the lower end of the extension 86, the detent 115 having contacted the head of the screw 93 so that the slide 105 is free to move toward the right, actuated by the lock bolt in locking direction to return the parts to the positions shown 5 in Fig. 5.

I have in Figs. 11 to 14, inclusive, shown my improved device in connection with a key lock, similar parts being indicated by similar but primed reference numerals, the key being indicated at 33' for locking and unlocking the bolt 24'.

I have in Fig. 14 shown a modification of my improved device, in which similar parts are indicated by similar but primed reference numerals. 15 Various of the parts are slightly different in form, and the springs are somewhat differently arranged, the spring 117 engaging a pin 136 on the slide 105', and the springs 83', 97' engaging a pin 137 on the supporting plate 41'. Their 20 functions, however, remain the same.

It is desired under certain circumstances and conditions that a minimum limit of time interval be provided between the beginning of opening of the lock and the full retraction of the lock bolt, 25 and I have provided means for accomplishing this in the modification exemplified in Fig. 15, in which similar parts are indicated by similar but double primed reference numerals.

These means in the present exemplification 30 control the release operation of the lever 81. It comprises a latch 141 for the bolt releasing mechanism. This latch remains in latching relation until the setting of the dial or winding wheel 131 for a minimum time delay, by rotation of the 35 shaft 62'' and angular movement of the pin 77'' thereon in winding or setting direction for a spaced distance from the lug 88'' equal to the minimum time interval desired as a matter of safety.

The latch 141 is provided with a keeper face 142, which coacts with a latching face 143 on a lug 144 on the lever 81''. The latch 141 is normally moved into latching relation with the lever 81'' by means of a spring 145, one end 45 of which is secured to the supporting plate 41'' by being clamped between pins 146, 147 in the supporting plate and a screw 148 threaded into the supporting plate.

The latch 141 is slidably mounted on the supporting plate and is held to the supporting plate by shoulder screws 149 threaded into the supporting plate and passing through slots 150 in the latch 141. The length of the slots with relation to the shank of the shoulder bolts limits 55 the sliding movement of the latch 141.

The relation of the bolt actuating slide 105'' and the detent lever 115'', shown in Fig. 15, is the same as that exemplified in Fig. 8 after completion of the unlocking movement of the lock bolt 24. The latch 141, when the keeper face 142 engages the latching face 143, maintains the keeper face 87'' in latching relation with the detent lever 115'' until the lever 81'' has been released from latched relation by the latch 141. 65 In order to effect such release, the shaft 62'' and its pin 77'' must have been moved through an angular distance sufficient for the pin 77'' to contact an actuating face 151 on a leg 152 of the latch slide 141 and to move such latch 70 slide, whereby its keeper face 142 will be out of range with the latching face 143 on the lever 81'', permitting retraction of said lever, limited by the pin 85''.

This angular distance in the present exemplifi- 75

cation amounts to a setting of the winding or dial wheel 131 for a time interval of at least 15 minutes, representing a minimum of safety interval between the beginning and the completion of the opening movement of the lock bolt. This safety interval may be longer, depending on the setting of the winding or setting wheel 131.

The pin 77" must move in retracting direction, throughout the angular space through which it has just been moved in such minimum time limit setting, before it can actuate the lug 83" to move the pivoted bars 91, 92, the bar 92" serving as a detent, out of obstruction with the keeper face 114" on the slide 105", in order to permit full unlocking movement of the lock bolt 24.

Having thus fully described my invention, what I claim as new and desire to secure by Letters Patent, is:

1. In combination, a locking part movable in release direction and in locking direction, a clock mechanism, and control means operatively disposed between said locking part and said clock mechanism comprising a movable part having operative connection with said locking part so as to be moved in consonance therewith, a clock control part actuated upon partial movement in release direction of said locking part for initiation of operation of said clock mechanism, a detent for said movable part actuated by said clock mechanism for release of said movable part whereby to permit release by said locking part, and a detent for said movable part for latching it against movement in locking direction.

2. In combination, a locking part movable in release direction and in locking direction, a clock mechanism, and control means operatively disposed between said locking part and said clock mechanism comprising a movable part having operative connection with said locking part so as to be moved in consonance therewith, a clock control part actuated upon partial movement in release direction of said locking part for initiation of operation of said clock mechanism, a detent for said movable part movable for release of said movable part whereby to permit release movement by said locking part, a detent for said movable part for holding it against movement in locking direction, and an operating part in association with said clock mechanism controlling holding effects of said keepers.

3. In combination, a locking part movable in release direction and in locking direction, a clock mechanism, control means operatively disposed between said locking part and said clock mechanism comprising a movable part having operative connection with said locking part so as to be moved in consonance therewith, and a pair of pivoted elements comprising a clock part control part, a detent, said clock control part slidable crosswise of its pivot and actuated by partial movement in release direction of said movable part for initiation of operation of said clock mechanism, and said detent coacting with said movable part for normally arresting unlocking movement of the same, and means between said clock mechanism and said detent whereby to actuate said detent by unwinding movement of said clock mechanism for release of said movable part.

4. In combination, a locking part and safety interval control means therefor comprising a clock mechanism, including a rotatable element for winding said clock mechanism, an actuating part rotatable in consonance therewith and retractable by the unwinding of the said clock mechanism, a detent for said locking part mov-

able into obstructing relation by winding movement of said rotatable element and into release relation by unwinding movement of said rotatable element, and a detent for holding said locking part in release relation, and means for release of said last-named detent by the winding movement of said rotatable element.

5. In combination, a locking part and safety interval control means therefor comprising a clock mechanism, including a rotatable element whose angular movement determines the duration of the safety interval and comprising an actuating part rotatable in consonance therewith and retractable by the unwinding of the said clock mechanism, a detent for said locking part movable into obstructing relation by winding movement of said limit part and into release relation by unwinding movement thereof, a detent for latching said locking part in release relation, and means for release of said last-named detent by the winding movement of said limit part.

6. In a safety interval lock control, the combination of a locking part, a slide having operative connection therewith, a clock mechanism, a clock control part having operative connection with said slide for clock operation by movement of said slide in unlocking direction for initiation of the safety interval, a detent for said slide, an operating part controlled by said clock mechanism for release of said detent at the termination of said safety interval whereby to free said locking part in unlocking direction, and a detent for holding said locking part in locking direction, said operating part having operative connection with said last-named detent for releasing the same.

7. In safety interval lock mechanism, the combination with bolt mechanism and clock mechanism of a movable part having operative connection with said bolt mechanism for being moved thereby, a clock control part actuated thereby having operative connection with said clock mechanism for initiation of the safety interval, a detent in connection with said last-named part, and a part having operative connection with said clock mechanism for release of said detent at the termination of said safety interval, said clock control part having an inclined face directed toward the engaging face of said detent for protecting the latter.

8. In safety interval lock mechanism, the combination with lock mechanism and clock mechanism, of a slide having operative connection with the lock mechanism, a combined slide controlling detent lever and clock controlling slide, said first-named slide provided with an abutment cooperating with said combined lever and slide for moving said clock controlling slide for initiation of the safety interval and arresting said first-named slide upon partial sliding movement of said first-named slide in unlocking direction, an operating lever coacting with said combined lever and slide, and an actuating part for said last-named lever having operative connection with said clock mechanism to release said combined lever and slide for terminating said safety interval.

9. In combination, a lock control part, a clock controlled part, a combined lever and slide therebetween, said combined lever and slide positioned for movement of said slide by said lock control part for initiating clock actuation and for latching of said lock control part, and said clock controlled part by such clock actuation acting on said combined lever and slide for releasing said lock con-

- trol part for retraction of said lock control part, and a latch between said clock controlled part and said lock control part to latch said lock control part in retracted position, said last-named 5 latch releasable by retraction of said clock controlled part.
10. In combination, a lock control part provided with a keeper, a clock controlled part, and a combined lever and slide therebetween, said 10 combined lever and slide positioned for movement of said slide for initiating clock actuation and for latching of said lock control part in release direction by said keeper, and said clock controlled part by such clock actuation acting on said 15 combined lever and slide for releasing said keeper for retraction of said lock control part.
11. In combination, a lock control part, a detent thereon, a clock controlled part provided with a keeper for said detent, and a combined lever and 20 slide between said lock control part and said clock controlled part, said combined lever and slide positioned for movement of said slide by said lock control part for initiating clock actuation and for latching of said lock control part in unlocking 25 direction, said clock controlled part by such clock actuation acting on said combined lever and slide for releasing said lock control part for full retraction of said lock control part, said detent and said keeper latching said lock control part in 30 unlocking position, and said keeper releasable from said detent by retraction of said clock controlled part.
12. In a safety interval lock mechanism, the 35 combination of a locking part, and control mechanism for controlling unlocking movement of said locking part after initiation of such unlocking movement including a minimum time limit device for insuring minimum limit of lapse of time for unlocking control of said control mechanism.
- 40 13. In a safety interval lock mechanism, the combination of a locking part, and control mechanism for controlling unlocking movement of said locking part after initiation of such unlocking movement including a minimum time limit device 45 for insuring minimum limit of lapse of time between such initiation of such unlocking movement and release of such locking part for full unlocking movement of such locking part.
14. In combination, a locking part movable in 50 release direction, a clock mechanism, and control means operatively disposed between said locking part and said clock mechanism comprising a movable part having operative connection with said locking part so as to be moved by said locking part, a clock control part actuated by partial movement in release direction of said locking part for initiation of operation of said clock mechanism, a detent for said movable part actuated by said clock mechanism for full release 55 movement of said movable part, and a latch to hold said detent in unlatching relation.
15. In combination, a locking part, a clock mechanism, and control means for said locking part comprising a part actuated by partial movement of said locking part for initiation of operation of said clock mechanism at the beginning of the safety interval, a latch to latch said locking part upon such partial movement, said latch actuated by said clock mechanism at the termination of the safety interval for release of said latch to permit full unlocking movement of said locking part, and a minimum time limit device for said latch. 5
16. In combination, a locking part and safety interval control means therefor comprising a clock mechanism including a winding element for said clock mechanism, an actuating part movable with the latter and retractable by the unwinding of said clock mechanism, a detent for said locking part movable into obstructing relation upon winding movement of said winding element and into 20 release relation upon unwinding movement of said winding element, and a latch for said detent holding said detent in unobstructing relation throughout a minimum limit of duration of unwinding movement of said winding element. 25
17. In a safety interval lock mechanism, the combination of a time movement, a bolt, a detent to obstruct unlocking movement of said bolt, connecting means between said bolt and said time movement to initiate a safety time interval for release of said detent, connecting means between said time movement and said detent to release said detent upon expiration of said safety time interval, and a detent to obstruct bolting movement of said bolt. 30
18. In a safety interval lock mechanism, the combination of a time movement, a bolt, a detent to obstruct unbolting movement of said bolt, connecting means between said bolt and said time movement to initiate a safety time interval for release of said detent, connecting means between said time movement and said detent to release said detent upon expiration of said safety time interval, a detent to obstruct bolting movement of said bolt, and a latch to maintain said last-named 45 detent in obstructing relation, said latch releasable by resetting of said time movement.
19. In a safety interval lock mechanism, the combination of a time movement, a bolt, a detent to obstruct unbolting movement of said bolt, connecting means between said bolt and said time movement to initiate a safety time interval for release of said detent, connecting means between said time movement and said detent to release said detent upon expiration of said safety time interval, and a minimum time limit device 50 obstructing resetting of said detent in such obstructing relation to compel minimum duration of said safety time interval. 55
